(Cl. D56—4)

To all whom it may concern:

Be it known that we, David M. King and Albert We wetzer, citizens of the United States, residing at Chicago, county of Cook, and State of Illinois, and Elgin, county of Kane, State of Illinois, have invented a new, original, and ornamental Design for a Case for a Radio of which the following is a specification, reference being had to the accompanying drawing forming part thereof.

Figure 1 is a plan view of a case for a radio, embodying our design;

Figure 2 is a front elevation of the same case;

Figure 3 is an end elevational view, looking from the left of Figure 1;

Figure 4 is a top plan view of the case with the cover open, showing the panel of the radio;

Figure 5 is a side elevational view of the case

with the cover open, looking from the right of Figure 4; and

Figure 6 is a front perspective view of the case with the cover open.

We claim:

The ornamental design for a case for a radio, as shown.

DAVID M. KING.
ALBERT WEWETZER.
